UNITED STATES PATENT OFFICE

138,532

DESIGN FOR AN ELECTRICAL CONNECTOR

Walter L. Miller, McGregor, Iowa

Application December 29, 1943, Serial No. 112,115

Term of patent 14 years

(Cl. D26—1)

To all whom it may concern:

Be it known that I, Walter L. Miller, a citizen of the United States, residing at McGregor, in the county of Clayton and State of Iowa, have invented a new, original, and ornamental Design for Electrical Connectors, of which the following is a specification, reference being had to the accompanying drawing, forming a part thereof.

Fig. 1 is a perspective view of an electrical connector showing my new design.

Fig. 2 is a similar perspective view with the parts separated.

Fig. 3 is a rear elevational view of the connector with the parts separated.

Fig. 4 is a top plan view; and

Fig. 5 is a bottom plan view of the connector.

I claim:

The ornamental design for an electrical connector, as shown.

WALTER L. MILLER.
